HANDLE

Filed Jan. 26, 1924

UNITED STATES PATENT OFFICE.

FRANK WILBAR GRIFFIN, OF GALESBURG, ILLINOIS.

HANDLE.

Application filed January 26, 1924. Serial No. 688,741.

To all whom it may concern:

Be it known that I, FRANK WILBAR GRIFFIN, a citizen of the United States, residing at Galesburg, in the county of Knox and 5 State of Illinois, have invented a new and useful Handle, of which the following is a specification.

The present invention relates to handles especially designed for carrying packages 10 and articles.

The primary object of the invention is to provide a handle of the detachable type which may be readily and easily secured to the cord, straps or the like, usually employed 15 for securing the package, thereby providing a package or article that may be readily and easily carried.

Another important object of the invention is to provide means for locking the handle 20 against displacement, when the same has been applied to a package for carrying purposes.

With the foregoing and other objects in view which will appear as the description 25 proceeds, the invention resides in the combination and arrangement of parts and in the details of construction hereinafter described and claimed, it being understood that changes in the precise embodiment of the 30 invention herein described, may be made within the scope of what is claimed, without departing from the spirit of the invention.

Referring to the drawing:

35 Figure 1 is an elevational view disclosing the handle as attached to a package.

Figure 2 is a bottom plan view of the handle.

40 Figure 3 is a sectional view taken on line 3—3 of Figure 1.

Referring to the drawing in detail, the handle is indicated at 5 and is formed with right angled end portions 6 having enlargements 7 at the free ends thereof, the en- 45 largements being formed with inwardly ex-

tended portions 8 slotted as at 9 to receive straps which may pass around the package to be carried.

Hook members 10 are formed on the enlargements and are especially designed for 50 engagement with twine, cord or other flexible means employed in tying packages. The enlargements 7 are formed with depressions in one of their respective faces, which depressions accommodate the pivoted keepers 55 11 that are designed to cooperate with the hook members 10 to close the hook members and prevent the cord or flexible member to which the handle is attached, from becoming displaced from the hook members. 60

The wall 10' of each depressed portion provides a stop for the pivoted keeper associated therewith, so that the strain directed to the handle will not operate to move the keepers to cause the handle to become 65 disconnected.

From the foregoing it will be obvious that by attaching a handle constructed in accordance with the invention, a package may be readily and easily carried, with the minimum 70 amount of exertion on the part of the person carrying the same.

I claim:

A removable handle including right angled end portions formed with enlargements, 75 one surface of each enlargement being cut away, each enlargement having a cut out portion extending from one edge thereof, defining a hook, a stop adjacent to the outer edge of each enlargement, a pivoted keeper 80 embodying a length of sheet metal bent upwardly to provide a finger grip, said pivoted keepers being mounted within the cut away portions of the enlargements to close the hook members, and said keepers adapted to 85 engage the stops to restrict movement thereof.

In testimony that I claim the foregoing as my own, I have hereto affixed my signature.

FRANK WILBAR GRIFFIN.
